UNITED STATES PATENT OFFICE.

FRANK PHILLIPS DORIZZI, OF BARNES, ENGLAND.

PENCIL-MAKING MACHINERY.

No. 918,979.

Specification of Letters Patent.

Patented April 20, 1909.

Application filed August 13, 1908. Serial No. 448,412.

To all whom it may concern:

Be it known that I, FRANK PHILLIPS DORIZZI, a subject of the King of Great Britain, and resident of 66 Elm Grove road, Barnes, in the county of Surrey, England, pencil manufacturer, have invented certain new and useful Improvements in and Relating to Pencil-Making Machinery, of which the following is a specification:

This invention relates to machinery for the manufacture of pencils and has for its main object to provide mechanical means for inserting the leads or other material preferably with the combination therewith of gluing means.

Leading means constructed in accordance with this invention comprise a series of hoppers arranged over a suitable bed along which the grooved boards to be leaded are slid and means connected to each of said hoppers for feeding a single lead or strip of other material to each groove in the board at the required moment. Said feeding means comprise for each hopper an outlet to said hopper of such width as to allow of the passage of a single lead therethrough, two or more pairs of arms mounted on a rocking shaft and disposed so as to receive therein one lead from said outlet and adapted to be then partially rotated so as to deliver said lead and to hold back the supply of leads in the hopper, means for causing such partial rotation of the arms and delivery of the lead at the required moment, and means may be provided for agitating the leads in proximity to the outlet to prevent them from becoming jammed.

Reference is to be had to the accompanying drawings forming a part of this specification in which similar characters of reference indicate corresponding parts in all the figures.

Figure 1 is a side elevation of one form of machine for gluing and leading pencils in accordance with this invention. Fig. 2 is a plan thereof. Fig. 3 is a cross section on line II-II of Fig. 2 drawn to an enlarged scale.

a is a hopper adapted to be charged with boards b already grooved for the reception of the leads, and with a groove on the reverse side thereof for guiding the board through the machine as will be hereinafter described and as is well known in connection with rounding machines for pencils. The boards b are charged into the hopper a with the lead grooves uppermost. Below the hopper a

are arranged a number of feeding rollers c adapted to feed forward the lowest board b along a bed d on which is a longitudinal projection adapted to engage the groove in the reverse side of the boards b and to guide said boards during their passage through the machine. On leaving the hopper a the board passes over a roller e between a guide e¹ and spring e² and its front end is engaged between a pair of rollers f, g, of which the lower g is driven by the same gearing as the feeding rollers and the upper f, called the timing roller, is frictionally rotated by the passage of the board b therebelow. From the timing roller f the boards b pass along the bed d below a roller 11 to the gluing means and thence below the leading means. The boards are thus fed through the machine in a constant stream and are successively glued and leaded. The timing roller f is designed according to the requirements of the machine, for instance where it is desired to supply leads to every alternate board, the circumference of said timing roller is equal to the length of two of such boards. The timing roller f is connected to the leading means by a lever h pivoted at i to the bed d of the machine, one end of said lever being provided with a friction roller j and adapted to be acted upon by a cam k on the timing roller f. The other end of the lever h is connected to and adapted to reciprocate a rack m with which mesh pinions n adapted to partially rotate rocking shafts o each carrying two pairs of arms p which select and deliver a single lead from the outlet q of each hopper r, to a chute 13.

s is a spring adapted to effect the return motion of the rack m, and t is a set screw for adjusting such return motion.

u are rods carrying cams v for agitating the leads before they are selected by the arms p, said rods being adapted to be rotated by a worm w and worm wheels such as x driven by a pulley y and belt z from a pulley 2 connected to the main driving means.

3 and 4 are fast and loose pulleys mounted on a shaft 5 having a bevel pinion 6 gearing with another bevel pinion 7 on a shaft 8 on which are mounted the roller g and the pulley 2.

9 are bevel pinions meshing with like pinions on shafts 10 on which are mounted the feeding rollers c.

The gluing means comprise a box 12 of metal (such as lead) or other suitable sub-

100

105

110

stance, open at the top and bottom and arranged above the bed so as to allow of the passage of the boards *b* between said box and the bed *d* and provided with means for supplying the said box with glue or other adhesive from a source of supply. The lower edges of two sides of said box are formed with projections following the configuration of the boards so as to leave a coating of adhesive on the boards as they pass below.

The leading means may be used in combination with the gluing apparatus described or with any other means for gluing.

If desired the machine can be arranged to 15 glue all the boards, but to lead alternate boards only as described, so that every pair of boards fed out of the machine may be placed together by hand, or if required by a further movement of the same machine. In another 20 form the machine may be designed to lead every board and may be connected with a second machine in which boards are glued but not leaded and a board may be taken from each machine and placed together by 25 hand or otherwise.

By the use of a machine constructed in accordance with this invention much hand labor and time are saved.

I claim—

30 1. Pencil making machinery, comprising the combination of a bed along which grooved boards are adapted to be slid, a series of hoppers arranged over said bed, and means connected to each of said hoppers for 35 feeding a single strip of material to each groove in the board at the required moment.

2. Pencil making machinery, comprising the combination of a bed along which grooved boards are adapted to be slid, a 40 series of hoppers arranged over said bed, an outlet to each hopper of such width as to allow of the passage of a single strip of material therethrough, rocking shafts disposed adjacent to said outlets, pairs of arms 45 mounted on said rocking shafts and deliver-

ing the said material substantially as set forth.

3. Pencil making machinery, comprising the combination of a bed along which grooved boards are adapted to be slid, a 50 series of hoppers arranged over said bed, an outlet to each hopper of such width as to allow of the passage of a single strip of material therethrough, rocking shafts disposed adjacent to said outlets, pairs of arms 55 mounted on said rocking shafts and adapted to receive one strip of material, a roller adapted to be frictionally rotated by the passage of the boards through the machine, and adapted to cause the partial rotation of said 60 rocking shafts substantially as set forth.

4. Pencil making machinery comprising the combination of a bed along which grooved boards are adapted to be slid, a 65 series of hoppers arranged over said bed, an outlet to each hopper of such width as to allow of the passage of a single strip of material therethrough, rocking shafts disposed adjacent to said outlets, pairs of arms mounted on said rocking shafts and adapted 70 to receive one strip of material, a roller adapted to be frictionally rotated by the passage of the boards through the machine, a cam on said frictionally rotated roller, a pivoted lever actuated by said cam, a rack 75 connected to said pivoted lever, and pinions on said rocking shafts meshing with said rack substantially as set forth.

5. Pencil making machinery, comprising the combination of a bed along which 80 grooved boards are adapted to be slid, a series of hoppers arranged over said bed, means connected to each of the said hoppers for feeding a single strip of material to each groove in the board at the required moment, 85 and means for gluing said boards.

FRANK PHILLIPS DORIZZI.
